P. DE SUSINI.
ETHER VAPOR MOTOR.

No. 508,447.

Patented Nov. 14, 1893.

UNITED STATES PATENT OFFICE.

PAUL DE SUSINI, OF PARIS, FRANCE.

ETHER-VAPOR MOTOR.

SPECIFICATION forming part of Letters Patent No. 508,447, dated November 14, 1893.

Application filed December 12, 1892. Serial No. 454,906. (No model.)

To all whom it may concern:

Be it known that I, PAUL DE SUSINI, a citizen of the French Republic, residing at Paris, France, have invented certain new and useful Improvements in Ether-Vapor Motors, of which the following is a specification.

It is the object of my invention to provide a motor or power apparatus in which the exhaust gas of a gas engine may be utilized to produce the vapor necessary to run the pistons of a vapor engine the said exhaust gas being used either directly from the gas engine or after having passed through the heating jacket of the vapor engine.

15 It is my object further to secure an advantageous co-operation between the vapor generator of the apparatus and the gas engine by utilizing the volatile liquid of the generator to keep the jacket of the gas engine cool, the 20 heat of the jacket produced by the frequent explosions reacting on the volatile liquid and tending to vaporize the same before it is returned to the generator.

In the drawings Figure 1 is an elevation of 25 my apparatus partly in section, and Fig. 2, is a plan of the left hand portion of the apparatus partly in section and Fig. 2" is a plan view of the right hand portion shown in Fig. 1, this being also partly in section.

30 The gas motor A discharges its spent gas through the pipe B, either to the vapor motor by the pipe a, or to the vapor generator by the pipe C and this is done by the means of a three-way cock c. This cock is intended to 35 regulate the passage of the gas through a and C and at the same time to prevent the gas passing through either of the pipes if desired. The spent gas passing through a is discharged into the jacket D of the cylinders E. F. of the 40 vapor engine and after heating the same it escapes through the pipe G which surrounds the vapor pipe H which leads from the vapor generator and feeds the cylinders E. F. By this arrangement the condensation of the 45 vapor is prevented. The gas passes from the pipe G into the generator through the chamber I to give up the rest of its caloric in order to produce the vapor from the ether which is contained in the chamber I' of the generator, 50 through which chamber the pipes A' pass for the circulation of gas which finally passes from the generator through the pipe J.

When the gas overheats the jacket D, it is cut off therefrom and sent directly to the

generator through the pipe C the cock c being turned for this purpose and by doing so heat is furnished the generator directly for the vaporization of ether. The liquid ether which is contained in the lower part of the generator circulates through pipe K to the 55 casing of cylinder L of the gas motor in order to cool off the walls of said cylinder by its contact with the same, while taking the heat up itself in order to produce the vapor of ether. Consequently the liquid ether circulates around the cylinder L takes the heat up therefrom and returns to the vapor generator 60 through the pipe M in the form of vapor or highly heated liquid.

The ether vapor after having produced its 70 effect in E and F escapes by N and into a suitable condenser; from there the liquid is taken back to the generator by a pump O to be used again.

Reference is made to my case filed December 19, 1892, Serial No. 455,668, as showing 75 some of the features included herein.

I claim—

1. In combination the gas engine, the vapor motor comprising a cylinder and piston, the 80 vapor jacket about the same, the generator, the exhaust pipe from the gas engine leading to the vapor jacket and thence to the generator, the second exhaust pipe leading directly to the generator and the valve for controlling 85 the said exhaust pipes, substantially as described.

2. In combination the gas engine, the vapor motor comprising a cylinder and piston, with the vapor jacket the vapor generator, the pipe 90 K leading from the lower part of the generator to the gas engine jacket to convey the cool volatile liquid thereto the return pipe M leading from the gas engine jacket to the generator, the direct connecting pipe from 95 the exhaust of the gas engine to the generator the indirect connection leading from said exhaust to the generator through the vapor jacket of the vapor motor to the generator and the valve for controlling said exhaust 100 connections, substantially as described.

In witness whereof I have hereunto set my hand in presence of two witnesses.

PAUL DE SUSINI.
